Primary Examiner — Katrina N Gonzalez

(57) **CLAIM**

The ornamental design for a cat scratching pad, as shown and described.

DESCRIPTION

1. Cat scratching pad

1.1 : Perspective

1.2 : Perspective

1.3 : Front

1.4 : Back

1.5 : Left

1.6 : Right

1.7 : Top

1.8 : Bottom

1.9 : Perspective view shown in a disassembled position

The parts shown by means of broken lines in the reproductions are not part of the claimed design; the explanatory curved bracket in fig. 1.9 shows the association of elements and forms no part of the claimed design.
